AUTOMATIC RECORD FEED AND REPEATER
DEVICE FOR PHONOGRAHS.Samuel Kohn, Bronx, N. Y., assignor to Radio
Corporation of America, New York, N. Y., a
corporation of Delaware

Application March 28, 1930, Serial No. 439,624

26 Claims. (Cl. 274—10)

This invention relates to improvements in phonographs, with special reference to types using flat circular disc records, having a continuous spiral sound groove of either the lateral or hill-and-dale type.

Such records are subject to certain disadvantages such for instance as their limited capacity, whereby the rendition of a lengthy song, story or musical work may not be completed on a single record, changing of which introduces brief interludes of silence that are highly objectionable, due to the hand work in releasing, removing and substitution of a continuing record.

It is also frequently desirable to enlarge upon the scope of a single record, as in the rendition of dance music, the objection to which it has been attempted to avoid by devices causing a repetition of playing the same record, but such devices are usually complicated and cumbersome.

I am aware that attempts have been made to produce so called multi-disc or progressively playing phonographs, but in all such attempts, so far as I am aware, the mechanism has been costly, cumbersome and complicated and subject to get out of order readily.

It is therefore an object of the present invention to provide a progressively playing phonograph constructed of few and simple parts and of a highly efficient character not subject to get out of order with even hard usage.

It is also an object of the present invention to provide means, including a carrier holding a plurality of records, moved automatically in sequence into position to deposit a new record upon the turntable when the previous record has been played, and also having means for repeating any selected record at will.

A further feature is in the provision of means to prevent damage to the records or needle, while the records are being transferred from their storage container into operative position, such transposition being rapid, completely automatic and timed from the end of the groove in the completed record to the beginning of the groove in the succeeding record.

Another aim is to provide means for playing records of different diameters with the same apparatus upon the mere substitution of a record carrier or support for the particular diameter of record to be played.

These advantageous objects are accomplished by the novel and practical arrangement of parts hereinafter described and shown in the accompanying drawings forming a material part of this disclosure, and in which:

Fig. 1 is a top plan view of the apparatus, showing a record in playing position.

Fig. 2 is a similar plan view, drawn to an enlarged scale, showing the operative parts in another position with the tone arm beyond the record and a new record partly lowered onto the turntable. 5

Fig. 3 is a side elevational view partially in section, showing the device with the lowermost record as about to be deposited upon the turntable and all the parts in the position shown in Fig. 2. 10

Fig. 4 is a plan view of the adjusting device.

The apparatus consists of a thin metallic plate 15, forming a partial cover for the supporting 15 stand on which the apparatus is secured.

Fixed on the plate 15, is a bracket 16 from which rises a pair of raised supports, respectively 17 and 18, through the latter of which extends a spindle 19, having attached at its end a tone-arm 20, a reproducer 21 being engaged on its outer free end carrying a needle 22, of any preferred type. 20

Except when in playing position, the tone-arm 20 normally rests upon a support arm 23 on 25 which it freely rides, the arm being fixed in the head 24 of a slidable spindle 25, extending axially through a raised boss on the bracket 16 and subject to a vertical movement by means further on described. 30

The mating support 17 acts as a bearing for a shaft 26, having fixed on its upper extending end a plate bracket 27, having downwardly flanged lateral edges 28 which are neatly fitted between 35 a pair of opposed flanges 29, extending from the sides of an arm 30, the elements 28 and 29 being pivotally connected by a pin 31 passing transversely through them.

The arm 30 is formed as part of a record carrier 32, suited to receive a plurality of records 33, the lowermost of which is supported by in-reaching lugs 34, arranged in spaced relation upon one side only of the ring 32, and directly opposite the midway position of the lugs 34 the ring has an inclined skirt. 40

This skirt is notched, as at 35, to produce a downwardly bent element 36 to which is attached a clip 37 carrying supports 38 extending inwardly toward the axis of the ring and serving as bearings for a roll 39 on which the lowermost 50 record 33 normally rests, thus providing a three-point support.

A similar roll 40 is carried by supports 41, spaced slightly above the roll 39, and at a greater radius so as to permit one of the records, 55

as 33' to enter between the rolls while being deposited in operative position on a turntable 42.

The turntable 42 is shown as mounted on a spindle 43, which is provided with an extending upper portion bevelled to readily engage with the axial opening in any of the records as placed thereon.

Below the turntable 42, the spindle 43 is provided on its lower end with a fixed pinion 46, arranged to drive a spur gear 47 mounted on a stud 48 encircled by a sleeve 49, the sleeve being provided with an enlarged friction annulus 50.

The stud 48 is engaged in the support plate 15, and it will be understood that the spindle 43 is rotated, preferably by an electric motor not shown, but to which current is conveyed by a spring switch device 52, having contacts 53-54 automatically opened by means further on described.

A lever 55 is pivoted to the plate 15 on a pin 56, the main arm of the lever containing a slot 57 engageable with a pin 58 carried in a cam plate 59, the main portion of which is fixed on 25 the shaft 26 to move with it.

The shorter arcuate arm of the cam plate 59 is downwardly bent at its extremity to form a cam surface and operates below the stem 25 of the arm 23, causing the arm to raise and lower in accordance with the position of the cam plate 59, and record carrier thereby raising and lowering the reproducer head 21 in an obvious manner.

Another arm 62 of the lever 55 has set in it a pin 63 on which is rotatably mounted an eccentric disc 64, this disc tending to be normally held in peripheral engagement with the friction annulus 50 by a coiled tension spring 65, one end of which is attached to the lever 55 and the other to a fixed point on the plate 15.

Thus it will be seen that the annulus 50 measurably controls the motion of the lever 55 by rotation of the disc.

Fixed on the upper side of the gear 47 is an upstanding lug 66 adapted to engage the convexly curved portion 67 of a lever 68 having a slot 68' and pivoted at 69 to the plate 15, and having at its outer free end, opposite the curved element 67, a sharply angled element 70.

Pivoted at 71, on the lever 68, is another lever 72, its free end 73 being arranged to stop beyond the point 70 of the underlying lever and is normally held out of such position by a coiled tension spring 74.

The lever 72 has adjacent its fulcrumed point 71 a bent lug 75 which operates against the edge of the lever 68 and is movable upon contact of the lever with a post 60 set in the plate 15. The arm 76 of the lever 55 is provided with an acute point 77 the same being engageable with an upturned lug 78 formed on a lever 79 pivoted on the pin 69 and provided with a down-turned lug 81, normally out of contact with the edge of the lever 68.

The outer portion of the lever 79 is provided with two steps 82 and 83, beyond which is an extension 84 on which is pivoted a pawl 85, the angular opposite end of which is moved outwardly by a spring 86 to engage one of the plurality 70 of teeth in an adjustment disc 87 mounted on a spindle 88, the pawl 85 being held against over operation by a lug 89 on the lever 79.

Fixed on the spindle 88 is a head 90 provided with a graduated disc 91, arranged to be manually operated and having a pointer 92 movable

with respect to a series of numerals 93 on the disc and also with relation to "stop" and "play" symbols 94 and 95, the disc also having an extension 96 bearing the word "constant".

Fixed on the spindle 88, below the toothed disc 87, is another disc 98, generally circular, but provided at one point with a depression terminating in a lug 99.

Impinging against the disc 98 is a tooth 100 formed on a lever 101, pivoted at 102 to the plate 15, and drawn normally into engagement with the discs 98 by a tension spring 103. The end of the lever 101 opposite the point 100 being adapted to make contact with a dog 104 pivoted at 105, and arranged to make operative contact with a spring arm 106, carrying the electric contact 54, so that, when the lever 101 is moved by the disc 98, the contacts 53 and 54 are separated to open the motor circuit.

Another index 110 is arcuately formed and secured to the plate 15 axially with relation to the post 111, the index having portions 112-113 at its ends respectively for 10 and 12 inch records, while its central portion 114 is arranged for repeating the record then in position on the turntable.

An index finger 115 is secured in the element 111, the upper end of which is slotted to fixedly receive a longitudinal reversible bar 116, having relatively long and short ends 116a and 116b respectively, for doffing the large or the small records, the upper edge of the bar being disposed in the plane of the bottom of the ring 32.

This bar is above and parallel with a lever 117 pivoted at 118 to the plate 15 and in turn has pivoted at its outer free end a lever 120, the tension spring 103 connecting the levers 101 and 120.

Fixed on the lower end of the element 111 is a plate having a series of angular faces as 122, 123 and 124 and 124', any of which may be selectively brought into position to contact the narrowed portion of the lever 117, depending upon whether it is desired to play 10 or 12 inch records, or if the record on the turntable is to be repeated.

The lever 68, containing a slot 68', movable on the fixed pin 69, is broadened and presents an arcuately curved element 125, having a concave cam slot 126 struck from the radius of the pin 69, and another portion 127 of the cam slot being struck from a different radius.

Movable in the cam slots is a pin 128 fixed on a flat lever 130 which in turn is pivoted on the pin 69 and contains an elongated slot 131 increasing in width towards its inner portion, which is disposed at a tangent to the pin 69.

Operable in the slot 131 is a pin, the upper end of which is arranged in two different planes respectively 132-133, this pin being fixed in a lever 135 which is fixed on the spindle 19 which in turn is keyed to the tone arm 20, so that as the tone-arm 20 is moved upon its axis the lever 135 is likewise moved and the pin will move in the slot 131 and actuate the lever 130.

The action of the lever 135 is limited by contact of the raised portion 133 of the pin, coming in engagement with the steps 82 or 83, according to the position of the lever 79.

Riding against the periphery of the cam 125 is a pin 136 carried at the end of a short lever 137 pivoted at 138 to the lever 130 and urged by spring 139 to retain the cam surface 126-127 in contact with pin 128.

The lever 120 has a forked outer end, one of the forks 140 being engageable with the pivot 78

69 to limit the movement of lever 120 in one direction while the other fork 141 makes engagement with the lower portion 142 of the pin 132-133 to move the tone arm from its fully extended position to a position to land on the record and then to move the tone-arm further inward to bring the stylus to the first lines of the record.

In operation the device works as follows:

Assume, as a starting point, the position shown in the drawings, Fig. 1, in which the reproducer 21 is seen as having moved inwardly almost to the end of the sound grooves of a record on the turntable, and the record carrier 32 resting in its outermost position, a stack of records having been previously deposited in the carrier. The eccentric disc is now out of contact with the annulus 50. Also, the arm or doffer 116 is in position to disengage the lowermost record from the stack. When the stylus 22 has reached the last sound groove of a record, the tone-arm having ceased to advance, the detent 70 on lever 68 remains in the path of the lug 66 and when struck by it, the lever 68 is rocked on its pivot against the lug 81 of lever 79 thus causing lever 79 to rotate on its pivot 69 to disengage the lug 78 from point 77 of lever 55 allowing lever 55 under the influence of its spring 65 to rotate on its pivot 56 to bring the periphery of the eccentric disc 64 into frictional engagement with the annulus 50 to be driven by it.

The disc 64 will now rotate in the direction of the arrow (Fig. 1) and by reason of the eccentricity of the disc, lever 55 will be rotated on its pivot, and through its slotted connection with pin 58, it will move the record carrier in the direction to be over the turntable in position to deposit new records.

As the record carrier 32 commences to move toward its position over the turntable, it carries with it the cam plate 59 which rides under the pin 25 causing the pin and its arm 23 to rise vertically, thus raising from the record, the tone-arm 20 until the stylus is entirely free of any record that might be upon the turntable.

Further movement of the record carrier toward the right, (as seen in Fig. 1) will cause the edge of the carrier to contact with the reproducer 21 and move it to its extreme outward position off the turntable, it being understood that the tone-arm will ride freely on arm 23 and be supported by it until again lowered onto the record.

As the record carrier approaches its innermost position, the nose 116a on arm 116 will engage the edge of the lowermost record, and further movement of the carrier beyond this point will cause the record to be moved into the escapement slot produced between the rolls 39 and 40, until the record is disengaged from the lugs 34; one end of the record will then drop by gravity, so that the centering hole of the record will engage directly over the turntable spindle 43.

The eccentric disc 64 has now reached the highest point of eccentricity with relation to the annulus 50 and further rotation will permit the record carrier to travel back again under the influence of spring 65 to resume its initial position. As the record carrier 32 moves back, the lowermost record having been engaged over the spindle 43 of the turntable, it will be dragged out of the escapement slot and allowed to fall by gravity onto the turntable.

The reproducer arm, too, under the influence of spring 103 acting on lever 120 follows the record carrier and returns to landing position on the record. This landing position is determined

by the position of the lever 79. As shown in Fig. 2, of the drawings, this lever is in position for playing 10" records and the pin 133 will contact with the shoulder 82 on lever 79 and thus prevent the tone-arm from moving further inward until after lever 55 has been moved back sufficiently to cause its edge 78 to contact with the underside of lug 78 to rock it on its pivot out of engagement with the pin 133 and then cause point 77 to again engage lug 78.

By this time the cam plate 59 has been withdrawn from under the shaft 25 and has permitted the tone-arm to be lowered onto the blank margin of the record disc just outside the first playing lines.

The fork 141 is now enabled to further advance the tone-arm inwardly until the stylus reaches the playing lines, it being understood that the outer arm 140 of the lever 120 contacts with shaft 69 to limit its movement in that direction.

The tone-arm is now free to advance to reproduce the record until the stylus again reaches the last sound convolution on the record.

Now as the tone arm 20 is moved to place the stylus in the starting position on the record the lever 130 is rotated around its pivot 69 and the pins 128-136 which yieldingly grip the element 125, swing the lever 68 on the pivot 69 in the lower end of the slot 68'. As the playing of the record proceeds and the tone arm 20 advances, thereby further rotating the lever 130, the pins 128-136 merely slide along the element 125 since the end of the lever 72 has contacted pin 60 and can be rotated no further in that direction. This continues until the pin 128 reaches the end of the cam surface 126. Now as it moves further onto the cam surface 127, the element 125 becoming narrower, the lever 68 is moved downwardly, as viewed in Fig. 2, until the upper end of the slot 68' rides on the pin 69 thus bringing the free ends of the lever 68 into the path of the lug 66. By means of the construction already described, the lever 68 is initially held away from the path of the lug 66, but is gradually moved into its path by downward movement of the lever 68 on the pin 69.

The lever 68 now presents the projection 67 in the path of the lug 66 and as the gear 47 rotates the lug 66 sweeps the end 67 of the lever 68 out of its path thus to present the edge 70 into its path, and this is permitted through the yielding frictional engagement of the element 125 between the pins 128-136; but, further advance of the tone arm 20, causing the lever 130 to continue to rotate on its pivot, rotates the lever 68 to remove the edge 70 from the path of the lug 66 so that the edge 70 will not be struck by the lug, and again as the gear 47 rotates, the lug 66 will sweep against the end 67 of the lever to again present the edge 70 into its path. This periodic engagement of the lug 66 with the end 67 of the lever continues until the stylus has reached the last sound convolution of the record, which convolution is usually circular and accordingly, there will be no further advance of the tone arm and the lever 68 will remain stationary with the sharply angled element 70 in the path of the lug 66 so that it will be struck by the lug 66, to rotate the lever 68 in a clockwise direction far enough to engage the lug 81.

This cycle will be repeated as long as there are records in the carrier to be deposited on the turntable providing of course, that the pointer 92 has been set to the numeral corresponding

with the number of records in the carrier desired to be played.

As stated above, as the last line on each record is reached, the lever 68 becomes operative and in rotating on its pivot engages lug 81 and rocks lever 79 around its pivot thus causing the pawl 85 to rotate ratchet 88 one tooth until the indent 99 on disc 98 has reached the position adjacent the tongue 100 of lever 101.

Then upon the next movement of pawl 85 the lever 101 will snap into the indent 99 and the opposite end of this lever will push element 104 against spring switch 106 to open the switch 52 and thereby stop the phonograph. If however it is desired to disengage the automatic stop to permit continuous playing, the indicator may be turned to "constant" and this movement presents to the pawl 85 the smooth surface 88', rendering the pawl inoperative to rotate disc 98 to position to allow tongue 100 to fall into indent 99 to open the switch.

The parts as shown in Figs. 1 and 2 are in position for playing 10" records but should it be desired to play 12" records, the stylus must be arranged to land on the margin of the larger record and this is accomplished by merely rotating the doffer plate 116, 180° to present the shorter end 116b to the record. This movement also results in rotating the cam disc on the post 111 to present surface 124' to the narrow end of lever 117 allowing the spring 103 to raise lever 120 to present the shoulder 83 to the pin surface 133.

If while records are still in the carrier, it should be desired to repeat any record, the doffer plate is turned about 60° from its playing position toward "repeat" thus preventing either nose 116a or 116b from doffing a record from the carrier.

As the tone-arm 20 is being moved off the record, it rotates with it the lever 135 which in turn moves the lever 120 through contact of the pin 133 with the fork 141, and the lug 120' contacts with the underside of lever 79 and rocks it on its pivot to present the shoulders 82 or 83 as the case may be in the path of 133.

Certain makes of disc records have the final convolution terminating in a quick spiral, or sometimes in an eccentric groove, in either of which case the tone-arm is given a rapid forward movement resulting in a rapid movement of the lever 130 and the lever 68.

This movement would remove projection 70 from the path of lug 66 and it would be necessary to wait until the lug again kicked the lever 68 to present projection 70 into its path for rendering operative the remainder of the mechanism, and to obviate this, the lever 72 is provided for quick action.

Upon the happening of the above described movements, the lever 68 will cause lever 72 to abut against the pin 60 and thus turn it on its pivot 71 to present the free end 73 into the path of the lug 66. When lug 66 contacts with the free end of the lever 73, it will cause lever 68 to rotate on its pivot through engagement of the downturned lug 75 against this lever and thus cause disengagement of the acute end 77 of the lever 55 from lug 78.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. In combination with a phonograph having a rotating element, a swinging element, a stylus carried by the swinging element to follow the sound convolutions of a record upon the rotating element and thus to propel the swinging element, and a record carrier adapted to deposit records successively onto the rotating element at the end of each reproduction, and mechanism to operate the same, two levers rotatably mounted on a common axis, means associated with the swinging element for rotating one of said levers, yieldable means connecting the two levers to cause the second lever to follow the movements of the first lever, means engaging a projection on the second lever to rotate it oppositely to the rotation of the first lever after the swinging element has reached the last sound convolution on a record upon the rotating element, means associated with the second lever to render said mechanism operative, when the forward movement of the swinging element has ceased, to move the record carrier into position to deposit a new record onto the rotating element, and to recede to initial position after the record has been deposited.

2. The combination with a phonograph having a rotating element, a swinging element, a stylus carried by the swinging element to follow the sound convolutions of a record upon the rotating element and thus to propel the swinging element, and a migratory record carrier adapted to deposit records successively onto the rotating element at the end of each reproduction and mechanism to operate the same; of three levers all mounted on a common axis, two of said levers being yieldingly engaged to cause the second to follow the movements of the first; the third lever being freely pivoted with respect to the other two, means associated with said record carrier for effecting migratory movement thereof, means on said third lever for normally locking said last named means to restrain it from moving said carrier, means associated with the swinging element for rotating the first of said levers, means engaging a projection of the second lever to rotate it oppositely to the rotation of the first lever after the swinging element has reached the last sound convolution on the record upon the rotating element, means on the third lever to be engaged by the second lever when such position has been reached for unlocking said first named means from said third lever whereby to render the mechanism operative, to move the record carrier into position to deposit a new record upon the rotating element and to recede to initial position after the record has been deposited.

3. The combination with a phonograph having a rotating element, a swinging element, a stylus carried by the swinging element to follow the sound convolutions of a record upon the rotating element and thus to propel the swinging element, and a migratory record carrier adapted to deposit records successively onto the rotating element at the end of each reproduction and mechanism including a lever for actuating said carrier to operate the same; three levers all mounted on a common axis, two of said levers being yieldingly engaged to cause the second to follow the movements of the first, the third lever being freely pivoted with respect to the other two, means associated with the swinging element for rotating the first of said levers, means on

the third lever for normally restraining the carrier actuating lever from actuating said carrier, and means engaging a projection on the second lever to rotate it oppositely to its rotation in response to said first lever when the swinging element ceases to advance or advances abnormally, to release the restraining means from the carrier actuating lever to permit the carrier to be moved thereby into position to deposit a new record onto the rotating element and to recede to its initial position after the record has been deposited, and means for effecting the deposit of a record from said carrier onto said rotating element incident to said migratory movement.

4. The combination with a phonograph having a rotating element and driving means therefor, a swinging element, a stylus carried by the swinging element to follow the sound convolutions of a record upon the rotating element and thus to propel the swinging element, and a migratory record carrier adapted to deposit records successively onto the rotating element at the end of each reproduction and mechanism including a lever for actuating said carrier to operate the same; three levers all mounted on a common axis, two of said levers being yieldingly engaged to cause the second to follow the movements of the first, the third lever being freely pivoted with respect to the other two, means associated with the swinging element for rotating the first of said levers, means adapted to actuate said actuating lever for moving the carrier to its various positions, means for normally urging said last named means into engagement with said driving means, means for normally restraining said urging means from operation, and means engaging a projection of the second lever to rotate it oppositely to the rotation of the first lever and release the restraining means when the swinging element ceases to advance or advances abnormally.

5. The combination with a phonograph having a rotating element, a swinging element, a stylus carried by the swinging element to follow the sound convolutions of a record upon the rotating element and thus to propel the swinging element, and a migratory record carrier adapted to deposit records successively onto the turntable at the end of each reproduction and mechanism including a lever for actuating said carrier to operate the same; of two levers mounted on a common axis, said levers being yieldingly engaged to cause the second lever to follow the movement of the first, a third lever, means associated with the swinging element for rotating the first of said levers, means engaging a projection of the second lever to rotate it oppositely to the first lever upon cessation of forward movement of and upon any abnormal movement of the swinging element, means on the third lever to restrain the carrier actuating second lever during normal playing movement of the swinging element and means including said lever to remove said restraint upon engagement of said means with said projection of the second lever.

6. The combination with a phonograph having a turntable and a record centering spindle thereon, of a migratory record carrier mounted to move over and beyond alignment with the turntable and to return to initial position and operatively connected to the phonograph driving mechanism, said record carrier comprising a ring having record supporting lugs on one side of its center and a record support and escapement slot on the opposite side, a stack of records in said

carrier and means to abut against the edge of, and by arresting its forward movement, to disengage the lowermost record from the lugs and move it into the escapement slot to cause it to drop onto the spindle when the record has reached the position of axial alignment with the turntable and before the carrier starts to resume its initial position.

7. The combination with a phonograph, of a migratory record carrier mounted to move over and beyond alignment with the turntable and to return to initial position and operatively connected to the phonograph driving mechanism, said record carrier comprising a ring having record supporting lugs on one side of its center and a record support and escapement slot on the opposite side, a stack of records in said carrier, means to arrest the forward movement of the lowermost record when it has reached a position of axial alignment with the turntable spindle while the record carrier continues to move to its position beyond alignment to move the record into the escapement slot, to partially disengage said record from the carrier to cause it to drop over the spindle.

8. The combination with a phonograph, of a migratory record carrier mounted to move over and beyond alignment with the turntable and to return to initial position and operatively connected to the phonograph driving mechanism, said record carrier comprising a ring having record supporting lugs on one side of its center and a record support and escapement slot on the opposite side, a stack of records in said carrier, means to arrest the forward movement of the lowermost record when it has reached a position of axial alignment with the turntable spindle while the record carrier continues to move to its position beyond alignment to move said record into the escapement slot and to disengage it from the lugs to cause it to drop over the spindle, said spindle serving also to retain the record in such position while the carrier recedes to completely release the record.

9. The combination with a phonograph, of a migratory record carrier mounted to move over and beyond alignment with the turntable and to return to initial position and operatively connected to the phonograph driving mechanism, said record carrier comprising a ring having record supporting lugs on one side of its center and a record support and escapement slot on the opposite side, a stack of records in said carrier, means to move the lowermost record into the escapement slot and to disengage it from the lugs to cause it to drop onto the turntable spindle when said record has reached the position of axial alignment with the spindle, said means comprising an abutment against which the edge of said record abuts to arrest its forward movement, means associated with the carrier to raise the tone-arm from the record and maintain it in raised position while it is being moved outwardly by the record carrier and until it is returned into position adjacent the first lines of the next succeeding record, said carrier also being adapted to contact with and move the tone-arm to a position beyond the record edge, and means to return the arm so its stylus is adjacent the initial playing lines of the record.

10. The combination with a phonograph, of a migratory record carrier, a stack of records in said carrier, means to automatically operatively connect the record carrier to the phonograph driving mechanism, to cause it to move into and

beyond alinement with the turntable and back to initial position, said record carrier comprising a ring having record supporting lugs on one side of its center and a record support and escapement slot on the opposite side, means to move the lowermost record into the escapement slot and to disengage it from the lugs to cause it to drop onto the turntable when said record has reached the position of axial alinement with the turntable, said means comprising an abutment against which the edge of said record abuts to arrest its forward movement, means associated with the carrier to raise the tone-arm from the record and maintain it in raised position while it is being moved outwardly by the record carrier and until it is returned into position adjacent the first lines of the next succeeding record, said carrier also being adapted to contact with and move the tone-arm to a position beyond the record edge, means to return the arm toward the playing lines of the record, means for limiting the inward movement of the tone-arm to cause the stylus to land on the record adjacent the first lines and means for disengaging said limiting means after the stylus has landed.

11. The combination with a phonograph having a tone-arm normally moved by and during the playing of a phonograph record, driving means therefor, a migratory record carrier, a member pivoted to move said record carrier alternately in opposite directions, a disc eccentrically pivoted to said member and means for tending to normally urge said disc into frictional engagement with the phonograph driving means, means for restraining the said urging means during normal playing of the phonograph, means to disengage said restraining means upon cessation of movement of, and upon any abnormal advancement of the tone-arm whereby the disc is brought into engagement to be rotated by the phonograph driving mechanism.

12. The combination with a phonograph having a rotating element, a swinging element, a stylus carried by the swinging element to follow the sound convolutions of a record upon the rotating element and thus to propel the swinging element, of a migratory record carrier adapted to deposit records successively onto the rotating element at the end of each reproduction, a member pivoted to move said record carrier alternately in opposite directions, a disc eccentrically pivoted to said member and means for tending to normally urge said disc into frictional engagement with the phonograph driving means, means for raising the swinging element from the record, means movable with the carrier for actuating said raising means, and means on the carrier for moving the swinging element to a position beyond but adjacent the record to permit the carrier to deposit a record upon the rotating element.

13. The combination with a phonograph having a rotating element, a swinging element, a stylus carried by the swinging element to follow the sound convolutions of a record upon the rotating element and thus to propel the swinging element, of a migratory record carrier adapted to deposit records successively onto the rotating element at the end of each reproduction, a member pivoted to move said record carrier alternately in opposite directions, a disc eccentrically pivoted to said member and means tending to normally urge said disc into frictional engagement with the phonograph driving means, means for restraining the said urging means during normal playing of the phonograph, means controlled by

said swinging element for rendering said restraining means ineffective to further restrain said urging means after the reproduction of a record whereby to render said urging means free to move said disc into engagement with said driving means to effect migratory movement of said carrier, means for raising the swinging element from the record, means movable with the carrier for actuating said raising means, and means on the carrier for moving the swinging element to a position beyond but adjacent the record to permit the carrier to deposit a record upon the rotating element.

14. The combination with a phonograph having a tone arm normally moved by and during the playing of a phonograph record, and driving means therefor, of a migratory record carrier, a member pivoted to move said record carrier alternately in opposite directions, a disc eccentrically pivoted to said member and means for tending to normally urge said disc into frictional engagement with the phonograph driving means, means for restraining the said urging means during normal playing of the phonograph, means to disengage said restraining means upon cessation of movement of, and upon any abnormal advancement of the tone-arm whereby the disc is brought into engagement to be rotated by the phonograph driving mechanism, means for raising the tone-arm from the record, means movable with the carrier for actuating said raising means, and means on the carrier for moving the tone-arm to a position beyond but adjacent the record.

15. The combination with a phonograph having a rotating element, a swinging element, a stylus carried by the swinging element to follow the sound convolutions of a record upon the rotating element and thus to propel the swinging element, of a migratory record carrier adapted to deposit records successively onto the rotating element at the end of each reproduction, a member pivoted to move said record carrier alternately in opposite directions, a disc eccentrically pivoted to said member and means for tending to normally urge said disc into frictional engagement with the phonograph driving means, means for raising the swinging element from the record, means movable with the carrier for actuating said raising means, means on the carrier for moving the swinging element to a position beyond but adjacent the record to permit the carrier to deposit a record upon the rotating element, and means to normally urge the swinging element from the position beyond the record edge, towards the first playing lines.

16. The combination with a phonograph having a rotating element, a swinging element, a stylus carried by the swinging element to follow the sound convolutions of a record upon the rotating element and thus to propel the swinging element, of a migratory record carrier adapted to deposit records successively onto the rotating element at the end of each reproduction, a member pivoted to move said record carrier alternately in opposite directions, a disc eccentrically pivoted to said member and means tending to normally urge said disc into frictional engagement with the phonograph driving means, means for restraining the said urging means during normal playing of the phonograph, means controlled by said swinging element for rendering said restraining means ineffective to further restrain said urging means after the reproduction of a record whereby to render said urging means free to move said disc into engagement with said

- driving means to effect migratory movement of said carrier, means for raising the swinging element from the record, means movable with the carrier for actuating said raising means, means on the carrier for moving said element to a position beyond but adjacent the record to permit the carrier to deposit a record upon the rotating element, and means to normally urge said element from this latter position towards the first playing lines.
17. The combination with a phonograph having a swinging element normally moved by and during the playing of a phonograph record, of a migratory record carrier adapted to deposit records successively onto the phonograph turntable at the end of each reproduction, a member pivoted to move said record carrier alternately in opposite directions, a disc eccentrically pivoted to said member and means for tending to normally urge said disc into frictional engagement with the phonograph driving means, means for restraining the said urging means during normal playing of the phonograph, means to disengage said restraining means upon cessation of movement of, and upon any abnormal advancement of the swinging element whereby the disc is brought into engagement to be rotated by the phonograph driving mechanism, means for raising the swinging element from the record, means movable with the carrier for actuating said raising means, means on the carrier for moving the swinging element to a position beyond but adjacent the record to permit the carrier to deposit a record upon the turntable, and means to normally urge the swinging element from this latter position towards the first playing lines.
18. The combination with a phonograph having a rotating element, a swinging element, a stylus carried by the swinging element to follow the sound convolutions of a record upon the rotating element and thus to propel the swinging element, of a migratory record carrier adapted to deposit records successively onto the rotating element at the end of each reproduction, a member pivoted to move said record carrier alternately in opposite directions, a disc eccentrically pivoted to said member and means for tending to normally urge said disc into frictional engagement with the phonograph driving means, means for raising the swinging element from the record, means movable with the carrier for actuating said raising means, means on the carrier for moving the swinging element to a position beyond but adjacent the record to permit the carrier to deposit a record upon the rotating element, means to normally urge the swinging element from this latter position towards the first playing lines, and means to arrest the return of the swinging element at a predetermined point.
19. The combination with a phonograph having a rotating element, a swinging element, a stylus carried by the swinging element to follow the sound convolutions of a record upon the rotating element and thus to propel the swinging element, of a migratory record carrier adapted to deposit records successively onto the rotating element at the end of each reproduction, a member pivoted to move said record carrier alternately in opposite directions, a disc eccentrically pivoted to said member and means tending to normally urge said disc into frictional engagement with the phonograph driving means, means for restraining the said urging means during normal playing of the phonograph, means controlled by 75 said swinging element for rendering said re-
- straining means ineffective to further restrain said urging means after the reproduction of a record whereby to render said urging means free to move said disc into engagement with said driving means to effect migratory movement of said carrier, means for raising the swinging element from the record, means movable with the carrier for actuating said raising means, means on the carrier for moving the swinging element to a position beyond but adjacent the record to permit the carrier to deposit a record upon the rotating element, means to normally urge the swinging element from this latter position towards the first playing lines, and means to arrest the return of the swinging element at a predetermined point.
20. The combination with a phonograph having a swinging element normally moved by and during the playing of a phonograph record, of a migratory record carrier adapted to deposit records successively onto the phonograph turntable at the end of each reproduction, a member pivoted to move said record carrier alternately in opposite directions, a disc eccentrically pivoted to said member and means tending to normally urge said disc into frictional engagement with the phonograph driving means, means for restraining the said urging means during normal playing of the phonograph, means to disengage said restraining means upon cessation of movement of, and upon any abnormal advancement of the swinging element whereby the disc is brought into engagement to be rotated by the phonograph driving mechanism, means for raising the swinging element from the record, means movable with the carrier for actuating said raising means, means on the carrier for moving the swinging element to a position beyond but adjacent the record to permit the carrier to deposit a record upon the turntable, means to normally urge the swinging element from this latter position towards the first playing lines, and means to arrest the return of the swinging element at a predetermined point.
21. The combination with a phonograph having a swinging element and a stylus, of a migratory record carrier adapted to deposit records successively onto the phonograph turntable at the end of each reproduction, a member pivoted to move said record carrier alternately in opposite directions, a disc eccentrically pivoted to said member and means for tending to normally urge said disc into frictional engagement with the phonograph driving means, means for raising the swinging element from the record, means movable with the carrier for actuating said raising means, means on the carrier for moving the swinging element to a position beyond but adjacent the record to permit the carrier to deposit a record upon the turntable, means to normally urge the swinging element from this latter position towards the first playing line, means to arrest the return of the swinging element at a predetermined point, means to lower the swinging element to cause the stylus to land on the record adjacent the first playing lines, and means to withdraw the swinging element arresting means after the stylus has landed.
22. The combination with a phonograph having a swinging element and a stylus, of a migratory record carrier adapted to deposit records successively onto the phonograph turntable at the end of each reproduction, a member pivoted to move said record carrier alternately in opposite directions, a disc eccentrically pivoted to said member

and means tending to normally urge said disc into frictional engagement with the phonograph driving means, means for restraining the said urging means during normal playing of the phonograph, 5 means controlled by said swinging element for rendering said restraining means ineffective to further restrain said urging means after the reproduction of a record whereby to render said urging means free to move said disc into engagement with said driving means to effect migratory movement of said carrier, means for raising the swinging element from the record, means movable with the carrier for actuating said raising means, means on the carrier for moving the swinging element to a position beyond but adjacent the record to permit the carrier to deposit a record upon the turntable, means to normally urge the swinging element from this latter position towards the first playing lines, means to arrest the return of 10 the swinging element at a predetermined point, means to lower the swinging element to cause the stylus to land on the record adjacent the first playing lines, and means to withdraw the swinging element arresting means after the stylus has landed.

23. The combination with a phonograph having a tone arm normally moved by and during the playing of a phonograph record, a migratory record carrier, a member pivoted to move said record carrier alternately in opposite directions, a disc eccentrically pivoted to said member and means tending to normally urge said disc into frictional engagement with the phonograph driving means, means for restraining the said urging means during normal playing of the phonograph, means to disengage said restraining means upon cessation of movement of, and upon any abnormal advancement of the tone-arm whereby the disc is brought into engagement to be rotated by the phonograph driving mechanism, means for raising the tone-arm from the record, means movable with the carrier for actuating said raising means, means on the carrier for moving the tone-arm to a position beyond but adjacent the record, means to normally urge the tone-arm from this latter position towards the first playing lines, means to arrest the return of the tone-arm at a predetermined point, means to lower the tone-arm to cause the stylus to land on the record adjacent the first playing lines, and means to withdraw the tone-arm arresting means after the stylus has landed.

24. The combination with a phonograph, of a migratory record carrier mounted to move over and beyond alignment with the turntable and to return to initial position and operatively connected to the phonograph driving mechanism, said record carrier comprising a ring having record supporting lugs on one side of its center and a record support and escapement slot on the opposite side, a stack of records in said carrier, means to arrest the forward movement of the lowermost record when it has reached a position of axial alignment with the turntable spindle 65 while the record carrier continues to move on to its position beyond alignment, to move said record into the escapement slot and to disengage it from the lugs to cause it to drop over the spindle, said spindle serving also to retain the record in such position while the carrier recedes to completely release the record, said arresting means being movably mounted for movement into and

out of the path of movement of said carrier, said arresting means, when swung out of the path of movement of said carrier, being adapted to be rendered inoperative so as to cause a repetition of reproduction of the record then on the turntable. 5

25. The combination with a phonograph having a rotating element, a swinging element, a stylus carried by the swinging element to follow the sound convolutions of a record upon the rotating element and thus to propel the swinging element, and a migratory record carrier adapted to deposit records successively onto the rotating element at the end of each reproduction, and mechanism including a lever for actuating said carrier to operate the same; three levers all mounted on a common axis, two of said levers being yieldingly engaged to cause the second to follow the movements of the first, the third lever being freely pivoted with respect to the other two, means associated with the swinging element for rotating the first of said levers, means on the third lever to restrain the carrier actuating lever, and means engaging a projection on the second lever to rotate it oppositely to the rotation thereof in response to said first lever when the swinging element ceases to advance or advances abnormally, to release the restraining means from the carrier actuating lever to permit the carrier to be moved thereby into position to deposit a new record onto the rotating element and to recede to its initial position after the record has been deposited, means for effecting the deposit of a record from said carrier onto said rotating element incident to said migratory movement, means for raising the swinging element from the playing position during advance of said record carrier, and means for moving the swinging element to a position beyond but adjacent the rotating element. 35 40

26. The combination with a phonograph having a rotating element, a swinging element, a stylus carried by the swinging element to follow the sound convolutions of a record upon the rotating element and thus to propel the swinging element, and a migratory record carrier adapted to deposit records successively onto the rotating element at the end of each reproduction, and mechanism to operate the same; a carrier actuating lever, three levers all mounted on a common axis, two of said levers being yieldingly engaged to cause the second to follow the movements of the first, the third lever being freely pivoted with respect to the other two, means associated with the swinging element for rotating the first of said levers, means on the third lever to restrain the carrier actuating lever, and means engaging the projection on the second lever to rotate it oppositely to the rotation of the first lever when the swinging element ceases to advance or advances abnormally, to release the restraining means from the carrier actuating lever to permit the carrier to move into position to deposit a new record onto the rotating element and to recede to its initial position after the record has been deposited, means associated with the record carrier for raising the swinging element from the playing position, and means for moving the swinging element to a position beyond but adjacent the rotating element. 55 60 65 70
